Primary Examiner — Calvin E Vansant(74) *Attorney, Agent, or Firm* — Dinsmore & Shohl LLP(57) **CLAIM**

The ornamental design for a vehicle wheel, as shown and described.

DESCRIPTION

FIG. 1 is a front perspective view of a vehicle wheel illustrating an embodiment of our new design;

FIG. 2 is a rear perspective view thereof;

FIG. 3 is a front view thereof;

FIG. 4 is a rear view thereof; and,

FIG. 5 is a side view thereof.

The broken lines in the drawings are included for the purpose of illustrating environmental structure and form no part of the claimed design. The side view depicted in FIG. 5 depicts a view of the vehicle wheel from a single side (e.g., a left side view or a right side view) and it should be understood that each of these side views are the same.
